UNITED STATES PATENT OFFICE.

FREDERIC BARR, OF NEW YORK, N. Y.; THE EQUITABLE TRUST COMPANY OF NEW YORK, OF NEW YORK, N. Y., A CORPORATION OF NEW YORK, EXECUTOR OF SAID FREDERIC BARR, DECEASED.

ELECTRIC SWITCH.

1,195,130.

Specification of Letters Patent. Patented Aug. 15, 1916.

Application filed June 3, 1914. Serial No. 842,570.

To all whom it may concern:

Be it known that I, FREDERIC BARR, a citizen of the United States of America, and residing at New York, in the county of 5 Kings and State of New York, have invented new and useful Improvements in Electric Switches, of which the following is a specification.

My invention relates particularly to 10 switches of the so-called lamp socket type and the objects of the invention are to provide a double break switch of simple, sturdy construction, having a relatively quick make and break, possessing high current carrying 15 capacity and one which shall be free from arcing effects.

In the drawing accompanying this specification I have illustrated in concrete form several practical embodiments of the invention, wherein these objects are attained by 20 double break switch mechanism embodying spring pressed contacts disposed one above and the other below a cam which serves as it is operated to force the upper contact upwardly into engagement with the contact portion of a circuit terminal and the lower contact downwardly into engagement with a relatively stationary contact.

A special feature consists in placing all 30 the switch mechanism in a chamber formed in the side of an insulating switch base, the contact portion of the circuit terminal being in the form of an angular foot by which the terminal is secured to a flange which forms 35 the upper wall of the switch chamber, the relatively stationary contact being secured to a flange which forms the bottom of the switch chamber and the cam being carried by a spindle which passes through the intermediate portion of the chamber.

Another feature of the invention consists in making up the spring pressed contacts in the form of a yoke-shaped member disposed at the side of the key spindle and having a 45 base portion suitably secured to the switch base and projecting spring contact arms lying on opposite sides of the actuating cam.

A further feature consists in making the contacts of light sheet metal and securing 50 them to the switch base by bossing up a portion of the sheet metal to produce collar-like

projections which are threaded to take securing screws which engage a part of the insulating base.

Various other features will appear as the 55 specification proceeds.

Figure 1, is a view of the rear side of a lamp socket switch embodying the invention, with a portion of the insulating base and the screw shell lamp terminal broken 60 away and shown in section. Fig. 2, is a front view of the same, showing the switch mechanism in the open circuit position, portions of the insulating base being broken away also in this view. Fig. 3, is a similar 65 view with the parts in the closed circuit position. Fig. 4, is a horizontal sectional view taken substantially on the plane of the line 4—4 of Fig. 3. Fig. 5, is a detached perspective view of the yoke-shaped spring 70 contact member employed in this first form of the invention. Figs. 6, 7 and 8 are similar views of other forms of such yoke members. Fig. 9, is a front view illustrating other modifications of the invention. Fig. 75 10, is a similar view showing certain other modifications. Fig. 11, is a vertical sectional view of the same taken substantially on the plane of the line 11—11 in Fig. 10. Fig. 12, is a drop perspective view of the 80 lower contact and spring pressed contact member in this form of the switch.

The switch parts are carried by a base 15 of suitable insulating material. This base is provided with a recess 16 in one side 85 thereof constituting a switch chamber and formed between an upper flange 17 and a lower flange 18.

20 is a circuit terminal provided with an angularly disposed foot 21 secured to the 90 top flange by a screw 22 and projecting inwardly into the switch chamber so as to form a relatively stationary upper contact.

24 is a lower relatively stationary contact secured on top of the bottom flange by a 95 screw 25 passed up through said flange into a screw seat in the contact.

Journalized in a bearing 30 in the insulating base, substantially midway between the upper and the lower contact and passing 100 transversely through the intermediate portion of the open-sided switch chamber is a

key spindle 31 on which is engaged by a suitable loose joint connection 32, a cam 33.

Arranged for engagement with the upper relatively stationary contact 21, is a spring 5 pressed contact in the form of a spring arm 35, and a similar spring pressed contact 36 is arranged to engage with the lower contact 24. The upper one of these spring arms extends above the cam and the lower one extends beneath the cam so that when the cam is turned to the position shown in Fig. 3, the tips of the arms are forced into engagement with the upper and lower contacts respectively.

10 In the forms of the invention illustrated in the first nine figures, the spring arms are integrally united in spaced apart relation by a connecting bar 40. At the point of connection with the bar, the spring arms are 15 usually formed with reverse bends 41 which may be angular in shape as shown and which serve in effect as hinges imparting increased resiliency to the spring action of the arms.

20 Various devices may be employed for securing the yoke-shaped contact member in position upon the insulating base. In the form shown in Figs. 2 to 5, the contact member is made with a base 44, integrally united 25 with the head or cross bar 40 of the yoke and disposed at an angle thereto, substantially parallel to the longitudinal axis of the spring arms. A screw 45, passed through an opening in the back of the insulating base into engagement with the base 30 portion of the yoke member, as shown in Fig. 4, serves to secure said member in place.

The contact members are preferably made of relatively light spring metal, such as 35 phosphor bronze and in order that the securing screws may be engaged direct in the metal of such members without the interposition of nuts and the like, I propose to "eyelet" "boss" or strike up the metal in 40 the base portion of such members into the form of a bushing or collar-like projection 50 which is internally threaded to take a securing screw. This provides a screw seat 45 of sufficient length to firmly hold a screw 55 and aside from the saving effected by the elimination of nuts for the screws, the parts can be much more readily and conveniently assembled.

The operation will be readily apparent 60 from Figs. 2 and 3. With the parts in the position shown in Fig. 2, the circuit is open at both sides of the cam. When the cam is turned into the position shown in Fig. 65, the upper spring pressed contact 35 is forced up into engagement with the contact portion of the circuit terminal 20 and the lower spring pressed contact 36 is forced downwardly into engagement with the lower relatively stationary contact 24. This lower 70 contact is in the illustration electrically

connected by its securing screw 25 with a center lamp terminal 60 so that in this position one side of the circuit is made from line terminal 20, through the arms and the back 40 of the yoke-shaped contact member to 70 the lower contact 24 and by screw 25 to the center lamp terminal. The other side of the circuit is provided for in the case illustrated by a screw shell lamp terminal 65, securing screw 66 and circuit terminal 67. This 75 securing screw, serves, as shown in Fig. 1, by being passed up through the bottom of the switch base to secure both the lamp terminal and the circuit terminal in place. The screw shell is additionally secured to the 80 base by a screw 68 passed up through the bottom flange 18 into engagement with a nut 69 seated in a pocket 70 provided by extending a flange 71 up from the bottom flange and laterally over the top of the nut. 85

Greater durability and an easier action of the switch parts is obtained by making the contact actuating cam of metal. The conductive quality thus given the cam also adds to the current carrying capacity of the 90 switch for with a metal cam parallel paths are provided for the current, one around the yoke member and the other straight across the cam, as will be clear from Fig. 3. When the cam is turned to "off" position a double 95 break occurs between the ends of the spring arms and the relatively stationary contact with the cam in parallel across the break. At the moment of break the yoke provides 100 a shunt around the cam, relieving the cam of current carrying need and preventing heating at the working surfaces of the cam and the contact arms. The double path for the current keeps the parts cool and this 105 with the elimination of heating at the cam gives the switch materially greater current carrying capacity.

Figs. 6, 7 and 8 illustrate variations in the form and the manner of mounting the yoke-shaped contact member. In the first 110 two of these views the reverse bends 75 formed at the ends of the spring arms are curvilinear, instead of angular in form and the members as a whole are mounted upon supporting brackets. In Fig. 6 bracket 76 is secured to the back of the member by a rivet 77 and the bracket is provided with a screw seat 79 to receive a securing screw 115 which may be passed down through the top or up through the bottom of the switch base 120 depending upon which way the bracket is to be mounted in the switch chamber.

In the form shown in Fig. 7, the supporting bracket 80 has an angular foot 81 projected off to the side of the contact member 125 and provided with a seat 82 to receive a securing screw passed through from the back of the switch base.

A simpler way of securing the contact member in position is that shown in Fig. 130

8 where the base portion of the member carries a tang or lug 85 which is passed through an opening to the back of the insulating base and there bent over or clenched to thereby fasten said member to the base.

5 The form of the invention illustrated in Fig. 9 is similar in a general way to the form first described. In this form the upper circuit terminal 87 has an angular contact portion 88 extending into the switch chamber as before, but the terminal is secured on the base by a screw 89 passed through from the back of the base, and engaged in a screw seat in the terminal. The 10 yoke-shaped contact member also has certain distinguishing features here in that the reverse bends are directed rearwardly so as to engage in recesses or pockets 90 on opposite side of an inwardly projecting rib 91, 15 and the angularly extending base portion 92 of said member extends completely across the back of the switch chamber. The contact member is in this way positioned and held in the switch chamber. It is usually 20 further secured by providing it with an opening 93 through which the key spindle passes.

25 In the construction illustrated in Figs. 10, 11 and 12 a conductive cam is always employed and the spring contact arms are separate instead of being connected together as in the previous forms. Thus the upper spring pressed contact is in the form of an introverted spring arm 95, secured to the 30 base by a screw 96 passed down through the top of the base and the lower spring pressed contact is in the form of an introverted spring arm 97 secured by a screw 98 passed up through the bottom flange of 35 the base. The upper spring contact is forced by the cam up into engagement with the angular foot or contact portion 21 of the circuit terminal and the lower spring contact is forced down into engagement with a 40 relatively stationary contact 99. This lower contact is as shown in Fig. 11, connected by the screw 98 with the center lamp contact 60. The lower spring contact while secured in place by screw 98 is insulated therefrom 45 and from the relatively stationary contact by surrounding the screw with an insulating bushing 100 where it passes through the opening 101 in the base portion of said spring contact and interposing a layer 102 50 of insulation between the underside of contact 99 and the top of the base portion of the spring contact. In this form also it is apparent that the circuit is broken at two points, namely between spring contact 95 and 55 upper contact 21 and between spring contact 97 and lower contact 99.

60 The construction of the cam in all the forms is such as to close the circuit with a quick action and to interrupt it with a quick 65 break. The breaking of the circuit at two

points and at opposite sides of the cam prevents arcing and renders the switch capable of carrying a considerable load. The few number of parts and the simple method of assemblage makes the switch a very durable 70 and at the same time a very economical one to manufacture.

What I claim is:—

1. In an electric switch, an insulating base having a recess in one side thereof forming 75 an open-sided switch chamber and flanges at the top and bottom of said recess, a circuit terminal having an angularly projecting foot portion secured to the top flange and extending within the switch chamber, a contact secured to the bottom flange and disposed within the switch chamber substantially opposite the foot of the circuit terminal, a key spindle journaled in the base and extending through the intermediate portion 80 of the switch chamber, a conducting cam on the spindle and spring pressed contact arms disposed above and below the spindle respectively and arranged to be forced by the cam upwardly into engagement with the 85 foot of the circuit terminal and downwardly into engagement with the lower contact, said spring pressed arms being adapted to break the circuit at two points with the cam in parallel across the break. 90

2. In an electric switch, an insulating base having a recess in one side thereof forming an open-sided switch chamber and flanges at the top and bottom of said recess, a circuit terminal having a foot portion secured to the top flange and disposed within the switch chamber, a contact secured to the bottom flange and disposed within the switch chamber substantially opposite the foot of the circuit terminal, a key spindle journaled 100 in the base and extending through the intermediate portion of the switch chamber, a cam on the spindle, and a yoke-shaped member located in the switch chamber at one side of the spindle having a base portion secured to the insulating base and spring contact arms disposed respectively above and below the cam in position to be forced by said cam upwardly into engagement with the foot of the circuit terminal and downwardly into 110 engagement with the lower contact. 115

3. In an electric switch, an insulating base provided with a switch chamber, a circuit terminal having a contact part extending into the upper portion of said chamber, a contact disposed in the lower portion of the chamber, a key spindle passing through the intermediate portion of the switch chamber, a conductive cam on the spindle within the chamber, a spring arm extending above the 120 cam into position to be forced thereby up into engagement with the contact part of the circuit terminal, a spring contact having a base portion disposed beneath the lower contact and an introverted spring arm dis- 125 130

posed above said contact in position to be forced by the cam down into engagement with the contact, insulation between the lower contact and the base portion of the spring contact, and a securing screw passed up through the bottom of the insulating base and through the insulation into engagement with the lower contact.

4. In an electric switch, an insulating base 10 having spaced apart top and bottom parts, a circuit terminal having an angularly projecting foot portion secured to the underside of the top part, a lower contact secured to the bottom part and disposed substantially 15 opposite the foot of the circuit terminal, a center lamp contact connected to said lower contact, a key spindle journaled in the base between the angular foot of the circuit terminal and the lower contact, a cam on the 20 spindle, spring-pressed contact arms disposed above and below the spindle respectively and arranged to be forced by the cam upwardly into engagement with the foot of the circuit terminal and downwardly into 25 engagement with the lower contact, said spring pressed arms being adapted to break the circuit at two points with the cam in parallel across the break, a screw shell lamp contact on the base, and a circuit terminal

on the base connected to said screw shell 30 contact.

5. In an electric switch, the combination of an insulating base, an upper circuit terminal mounted on the base having a laterally extending contact portion, a lower relatively stationary contact secured on the base opposite the contact portion of the upper circuit terminal, a key spindle journaled in the insulating base intermediate the lower stationary contact and the upper contact portion of the terminal, a cam on the spindle, a yoke-shaped member at one side of the spindle having a base portion and spring contact arms disposed respectively above and below the cam in position to be forced by the 45 cam upwardly into engagement with the contact portion of the terminal and downwardly into engagement with the lower contact, a bracket engaging said base portion and provided with a screw seat, and a securing screw 50 passed through the back of the insulating base into engagement with said screw seat to thereby secure the yoke-shaped member on the base at the side of the spindle.

FREDERIC BARR.
